(57) CLAIM

The ornamental design for a stabilizer pad, as shown and
described.

DESCRIPTION

FIG. 1 is a top, front, left side perspective view.

FIG. 2 is a left side elevational view, the right side being a
mirror image thereof.

FIG. 3 is a front elevational view.

FIG. 4 is a rear elevational view.

FIG. 5 is a top plan view; and,

FIG. 6 is a bottom plan view.

The broken lines shown throughout the drawing are for
illustrative purposes only and form no part of the claimed
design.
